UNITED STATES PATENT OFFICE.

HENRY A. PITCHER, OF NEILLSVILLE, WISCONSIN.

MAGAZINE-GUN.

SPECIFICATION forming part of Letters Patent No. 433,420, dated July 29, 1890.

Application filed April 23, 1889. Serial No. 308,248. (No model.)

To all whom it may concern:

Be it known that I, HENRY A. PITCHER, a resident of Neillsville, in the county of Clark and State of Wisconsin, have invented certain

5 new and useful Improvements in Magazine-Guns; and I do hereby declare the following to be a full, clear, and exact description of the invention, such as will enable others skilled in the art to which it pertains to make and use 10 the same.

My invention relates to an improvement in magazine-guns adapted to be automatically reloaded and cocked at each discharge by utilizing a portion of the explosive gas generated by the combustion of the powder in the gun-barrel; and it consists in the peculiar construction and combination of devices hereinafter described and claimed.

This invention is an improvement on the 20 magazine-gun described and claimed in Letters Patent of the United States No. 397,143, granted to me February 5, 1889.

In the accompanying drawings, Figure 1 is a side elevation of my improved automatic 25 magazine-gun. Fig. 2 is a similar view of the reverse side thereof. Fig. 3 is a longitudinal sectional view of my improved automatic magazine-gun, showing the parts of the same in position at the instant after firing. Fig. 30 4 is a similar view on a different plane, showing the parts of the same in position after firing. Fig. 5 is an enlarged elevation, partly in section, showing the parts of the gun in position locked ready to fire. Fig. 6 is a top 35 plan view with the top plate of the lock-case removed. Fig. 7 is a vertical transverse sectional view taken on the line $y-y$ of Fig. 3. Fig. 8 is a longitudinal horizontal sectional view taken on the line $x-x$ of Fig. 3.

40 Above the barrel B is a magazine-tube, in which is the usual spring-pressed follower. Below the barrel is a tube D, in the rear end of which is secured a cylindrical chamber A, whose rear end communicates with the barrel 45 at a point near the rear end of the latter by a vent E, which is adapted to be closed by a screw-plug or valve F. At one end of the valve is an arm or pointer F², which works on an indexed radius F³ on one side of the lock-case and serves to indicate the position of the 50 valve.

C represents a piston, which operates and is

fitted in the cylinder A and has an enlarged head H, that works in tube D. A coiled spring M arranged in the tube passes rearward on 55 the piston.

G represents a drive-rod, which is guided in a groove through the lock-case at the lower side of the tube D and has its front end attached rigidly to the piston-head H. 60

In the sides of the lock-case in rear of the barrel and below the level of the same are openings which are closed by plates a b, which are adapted to be removed when necessary. The plate a on the right-hand side of the lock-case has a downwardly-curved longitudinal slot c, and the plate b has an opening d at its front end of suitable size and shape for the discharge and ejection of a cartridge-shell.

The segment I is adapted to travel longitudinally in the lock-case, and has the pivoted tumbler P at some distance from its front end adapted to be engaged by the rear end of the drive-rod G. The pivot-pin P¹² is rigidly secured to the segment and works in an oblique 75 slot P¹³ in the tumbler, so that the latter is adapted to play obliquely on its pivot as well as to turn thereon.

Within the tang at the rear of the lock-case is a recess f, in which operates a radius-lever r. 80 The latter has its lower end pivoted on a pin s and has a short arm r', to which is pivoted a stirrup i.

The breech-bolt k is arranged in that part of the lock-case immediately in rear of the 85 barrel and has the depending shoulder e, and on opposite sides of the shoulder, in a line with the longitudinal axis of the breech-bolt, are grooves l m. A tongue n is set in an opening o in one side of the lock-case and enters 90 the groove l, and a similar tongue p is set in an opening i' in the opposite side of the lock-case and enters the groove m. The said tongues and grooves thereby serve as ways to guide the breech-bolt, as will be understood. 95

On the rear upper corners of the projecting sides of the shoulder e are formed cams q. In the lower side of the shoulder is journaled an anti-friction roller t, that bears and travels on a horizontally-arranged guide-arm u, the latter being secured at its front end to a shoulder formed in the lock-case by a screw v. The drive-rod travels under this guide, and the downwardly-curved cam x at the rear end

of the latter causes the said drive-rod when forced rearward to bend down and conform to the contour of the lock-case, and thereby retain its engagement with the tumbler.

5 It will be observed by reference to Fig. 3 that when the segment is in its normal position at the forward limit of its stroke the tumbler is disposed in a horizontal position, with its upper side bearing under the cam-arm x and its lower side engaged by the spring h . The stroke of the piston C is such that when the piston moves rearward, for the purpose to be presently described, the drive-rod G forces the tumbler P rearward, and the latter is maintained in its horizontal position until its front end clears the rear end of the cam-arm, when it turns on its pivot and becomes released from the drive-rod, as shown in Fig. 4. The lower side of the lock-case is 10 concaved at a point slightly in advance of the trigger-guard to form the depression P¹⁴, which permits the tumbler to turn, as before described. On the ensuing forward movement of the segment the tumbler, being carried with it, has its upper end engaged by the rear end of the cam-arm x , which causes the tumbler to complete a rotation and become disposed under the cam-arm in the position before described, and shown in Fig. 3, with 15 the exception that the end of the tumbler which was formerly foremost is now rearmost, the tumbler turning or reversing its position at each stroke of the piston C. The oblique slot P¹³ in the tumbler, in which the pivot works, adapts the tumbler to thus reverse its 20 position and to lie snugly under the cam-arm x with either end foremost, as will be apparent.

On the inner side of the tongue p , at the rear-end thereof, is formed a cam q' , and in the 25 front end of the groove m is located a spring-pressed extractor-hook w , which is caused to engage the flange of the cartridge-shell in the breech of the barrel when the breech-bolt is at the forward limit of its movement, and is 30 caused to withdraw the said shell from the barrel when the bolt moves rearward. An arm X is formed at the rear end of the said hook, and when the breech-bolt reaches the 35 rearward limit of its movement the said arm engages the cam q' , and thereby partly turns the hook on its pivot and causes the same to liberate the shell of the discharged cartridge.

Link-arms y have their front ends pivoted 40 in notches formed in the rear side of the depending shoulder e of the breech-bolt. The rear ends of the said link-arms have curved faces z and are pivoted to links a' , the lower sides of which are pivotally connected to the 45 segment I. The links a' have curvilinear-surfaced projections formed at right angles to the pivoted ends, which when the lock is closed lie up to and under the septum-shoulder b' , against which the faces of the 50 link-arms y abut, so that when the segment I is forced to the rear a rolling motion is imparted to the links a' , which at the start has

50 a powerful fulcrum-leverage upon the link-arms y , and afterward a quicker motion and causes the link-arms y to descend at their rear ends and the faces z thereof to be cleared from the abutting septum b' of the lock-case, when they are permitted to proceed rearward with the segment I until the breech is sufficiently withdrawn. The function of the said 55 septum b' and of the faces z of the link-arms is to lock the breech-bolt firmly when at the front limit of its movement and prevent it from being forced backward by the shock of the explosion when the gun is fired. 60

The firing-pin c' is guided in the breech-bolt in the usual manner, and has a slot d' near its front end, which is engaged by an arm e' , that projects from one of the link-arms y , the said arm e' serving to retract the 65 firing-pin when the breech-bolt is drawn rearward by the link-arms. The hammer T is pivoted in the lock-case on a pin g' , and has its percussion-arm h' arranged in the path of the breech-bolt and provided with an anti-friction roller R, hence the hammer is automatically cocked by the breech-bolt when the latter moves rearward after each discharge. 70

The hammer-spring k' has its rear end secured to the bottom of the lock-case, and the front end of the said spring bears under an anti-friction roller l' journaled in the hammer. The trigger N has rearwardly-extending arms O, and pivoted on the same pin with the trigger is a curved sear o' , the front end of which is adapted to engage the usual notches p' of the hammer to hold the latter at half and full cock. A spring s' presses upon the sear o' at its free end and holds the latter in engagement with the notches in the hammer when not pressed in an opposite direction by the trigger-arm O. While the segment I is moving either forward or rearward its lower side is in engagement with studs U on the outer sides of the arms O of the trigger, and hence the latter is held in position with the hammer locked at full-cock. Near the rear end of the segment, in its lower side, is a recess t' , which clears the trigger-arm studs 100 when the breech-bolt and the segment are at the forward limit of their movements, and hence enable the trigger to be pulled to disengage the sear from the hammer. It will be 105 obvious from the foregoing description that it will be impossible for the gun to be discharged prematurely. 110

The cartridge-carrier K is composed of three sections a^2 , b^2 , and c^2 , the latter being located between the rear ends of the others. 115 An inclined opening d^2 is made between the rear ends of the sections a^2 b^2 and in communication with an opening in the top plate L of the lock-case, through which a cartridge may be inserted into the carrier by hand. 120 The section a^2 has a lateral flange f^2 formed in its upper side near its front end, the lower side of the said section being cut away, as shown, and the section b^2 is provided near its 125

forward end at its upper and lower sides with flanges g^2 h^2 , respectively. A spring i^2 is arranged under the front end of the section c^2 and bears on the upper side of the breech-bolt and serves to raise the front end of the said section and cause it to abut against the base of a cartridge when the carrier registers with the magazine, and thus the said section c^2 constitutes a stop to limit the movement of the cartridge, as will be readily understood. At the rear ends of the sections a^2 b^2 are depending arms k^2 in the paths of the cams q . The under side of the section a^2 is provided with a re-entering cam or curve p^2 . When the breech-bolt moves rearward, the cams q thereof engage the cams k^2 of the sections a^2 b^2 , and thereby depress the front ends of the same and cause their upper flanges to bear downward on the live cartridge partly enclosed within them, and also the lower flange h^2 of section b^2 to bear upon the exploded shell underneath, which has been drawn from the barrel by the cartridge-hook w , and thereby dislodges the exploded shell from the head of the breech-bolt, so that it may be ejected through the opening d by the forward motion of the breech-bolt. It also assists in retaining by its downward force the live cartridge in position to enter the barrel by the same forward movement of the breech-bolt. The depressed front ends of the sections a^2 b^2 are held in rear of the magazine in such manner as to prevent the cartridges therein from moving into the lock-case.

The section b^2 somewhat resembles the form of a longitudinal section of tubing, its hollow or inside diameter corresponding in size to the head of the cartridge. When it is tilted downward by the contact of cam q against the projection at its rear end, its lower edge or flange h^2 forms, together with the tongue, which lies in the longitudinal groove within the side of breech-bolt underneath the section a^2 , a guide for the live cartridge in its forward movement into the barrel. At the initial forward movement of the breech-bolt the cams q thereof clear the arms k^2 of the sections a^2 b^2 , and as the breech-bolt moves forward the front upper corners of the shoulders e engage the lower sides of sections a^2 b^2 , thereby raising the front ends of the said sections into alignment with the magazine, and the carrier being thus caused to register with the rear end of the magazine, a cartridge from the latter will be moved rearward into the carrier, in the manner well understood by those skilled in this art, and caused to abut against the front end of the pivoted section c^2 . A rod m^2 connects the longer arm of the radius-lever to the rear end of the segment I . The rear end of the drive-rod G works under the guide u and is directed by the latter in its engagement with the tumbler P . A spring h presses up under the said tumbler and causes the latter to slide in contact with the guide. A finger-knob S has its shank working in

the slot c of the plate a and is attached to the segment, and consequently the latter, and hence the entire lock mechanism may be operated by hand when desired.

When the piece is discharged, a portion of the gas passes through the vent E into the cylinder A and forces the piston C forward therein against the tension of the spring M and causes the drive-rod G to lock against the tumbler P . The ensuing reaction of the spring M causes the piston to be driven rearward in the cylinder, and the drive-rod communicates rearward movement to the segment, which rearward movement is communicated to the breech-bolt by the link-arms y and to the radius-lever r by the rod m^2 . The spring g , connected to the radius-lever, acts as a buffer to deaden the shock and prevent injury to the parts of the lock mechanism. The recoil-spring, together with the rod m^2 , serves to throw the breech-bolt and locking devices forward and complete the operation of loading the gun.

From the foregoing description it will be understood that the lock mechanism is operated automatically at each discharge of the gun and caused to eject the empty shell, reload, and cock the hammer, and therefore after each discharge it is only necessary to press the trigger to cause the gun to be again fired, and this may be kept up until the magazine has been emptied.

It will be observed by reference to Figs. 3, 4, and 5 that the upper and lower sides of the curved portion of the lock-case and the lower side of the segment are drawn from the same center, and therefore are concentric. This construction is highly advantageous for the reason that it adapts the curved segment to move back and forth in the curved portion of the lock-case with the smallest possible degree of friction, thereby increasing the efficiency of the gun and rendering it easy to operate the same.

Having thus described my invention, I claim—

1. In an automatic gun, the combination of the segment I , pivotally connected to the lock mechanism, the radius-lever, the recoil-spring having one end fixed and the free end pivotally connected to one end of the radius-lever, the rod m^2 , pivotally connected to the opposite end of the radius-lever and to the segment, said elements being appropriately located in the stock of the gun, and the devices, substantially as specified, for operating the segment and the lock mechanism, substantially as described.

2. The combination, in a gun-lock mechanism, of the traveling segment and operating devices therefor, the link-arm connected to said segment and to the breech-bolt and thereby operating the latter, and the arm projecting from the link-arm and engaging the firing-pin to retract the latter, substantially as described.

3. The combination, in the lock mechanism of a gun, of the breech-bolt, the slotted firing-pin therein, the traveling segment and operating devices therefor, the link-arm connected to said segment and to the bolt and thereby operating the latter, and the arm projecting from the link-arm and engaging the slot of the firing-pin to retract the latter, substantially as described.
4. The combination, in an automatic gun, of the longitudinally-traveling segment, and devices, substantially as set forth, for operating the same, the pivoted trigger having the rearwardly-extending arm in the path of the segment, the latter having the recess near its rear end adapted to clear the said arm, and the frame in which the trigger is mounted, having the recess in which the arm may be pressed by the segment in its rearward movement, substantially as described.
5. The pivoted cartridge-carrier, comprising the central section c^2 and the side sections a^2 b^2 , each having the cams, substantially as specified, in combination with the longitudinally-movable breech-bolt arranged under the said sections and having the cams to engage the cams on the sections and operate the latter, substantially as described.
6. The curved lock-ease having the upper and lower sides concentric, the curved seg-

ment concentric with the lower side of the lock-ease and adapted to move forward and backward therein, devices, substantially as specified, to operate the segment, and the lock mechanism connected to the said segment, 35 substantially as described.

7. The lock-case having the cam q' in its inner side, in combination with the breech-bolt and the spring-pressed extractor-hook pivoted in a recess in one side of the breech-bolt at the front end thereof, the said extractor-hook having a rearwardly-extending arm provided with a cam X , arranged in the path of the cam q' , substantially as described.

8. In an automatic magazine-gun, the plug 45 F, adapted to open and cut off communication from the bore of the cylinder to the bore of the barrel, and having the arm or pointer attached to the plug and located on the outside of the lock-case, in combination with the indexed radius on the outside of said lock-case, 50 substantially as described.

In testimony whereof I have signed this specification in the presence of two subscribing witnesses.

HENRY A. PITCHER.
